UNITED STATES PATENT OFFICE.

JOHN J. SHEVLIN, OF CORONA, NEW YORK.

GRATE-BAR.

1,250,369.

Specification of Letters Patent. Patented Dec. 18, 1917.

Application filed February 10, 1915. Serial No. 7,266.

To all whom it may concern:

Be it known that I, JOHN J. SHEVLIN, a citizen of the United States, residing in Corona, borough of Queens, in the county of 5 Queens and State of New York, have invented a new and useful Improvement in Grate-Bars, of which the following is a specification.

This invention relates to new and improved construction of grate bars for furnaces; and the main object of the same is to provide a grate bar that may be removed from the rocking arm without in any manner having to tilt the rocking arm or to dis- 10 turb any other grate from its normal position.

Another, and one of the main objects of the invention is to provide the grate bar proper with overlapping and underlapping 20 ends, together with slots into which the head of the rocking arm rests, and by which said section or sections may be readily removed or replaced without disturbing others than those desired, and as has already been noted, 25 without detaching or operating any other part to so remove such other part or parts. These improvements permit of the grate-bar being simplified, and made more durable, and at the same time made more economical, 30 in cost of construction as well as in operation.

With these and other objects in view, the invention consists of certain features of construction above noted, also in the combination and arrangement of parts, as will be 35 more fully described and specifically pointed out in the claims.

In the accompanying drawing which forms part of this specification, Figure 1 is 40 a vertical sectional view through the grate, other parts being omitted for clearness; Fig. 2 is a detached sectional view of the rocker arm, Fig. 3 is a detached sectional view of one of the grate sections, and Fig. 4 is a sectional view showing a modification of the slot.

Like reference characters designate like parts throughout the several views of the drawings.

50 The coincident feature of this invention that is common with all grate bars is, that they are made in sections, and these various sections are so arranged that they may be operated by any suitable or well known devices for discharging the ashes and clinkers that may accumulate within the fire box.

But in all such grates there are more or less complicated ways of connecting and detaching the individual sections, for repair or to replace the same.

60

Referring to Fig. 1, the front of the fire box is provided with a bearing bar 4, which has formed at its upper edge a laterally extending lip 5, said lip being triangular in cross section and terminating in an edge 6. 65 The bearing bar is provided with a projection on which the side carrier is supported and maintained.

A side carrier 7 is provided to which the rocking arm 8 is suitably secured. The rocking arm consists of a head 9, a neck 10, and an enlarged portion 11 below which is a base flange 12. Extending downwardly from the base flange 12, and preferably at the center thereof, is a finger or bar 13 to which is 70 adapted to be secured a link 14. Link 14 has its upper end 15 bifurcated to embrace the finger 13, to which it is secured in any suitable and convenient manner, as by the bolt 16. The lower end of said link 14 is 75 suitably secured to an arm or rod 17, which is usually employed in furnaces, but it will be understood that such means, or any other may be employed for rocking the various sections of the grate bar.

85

Referring particularly to Fig. 3, it will be seen that the grate bar 18 is provided with angular lips 19, and 20, the former extending below the top face of the bar, and which conforms to the same angle as that on the 90 lip 5 on the bearing bar 4. The grate bar on the upper side may be of any well known design wherein the maximum amount of space may be provided to retain the fuel, and at the same time to provide the maximum 95 amount of space to allow the air to pass through for proper combustion. Referring now to the opposite end of said grate bar 18, it will be seen that the lip 20 conforms in all essential particulars to that formed on the 100 front bearing bar 4, by so providing the grate bar with the lips so arranged, permits of any of the various sections that make up the grate, being interchangeable. Below the grate bar is arranged a flange 21, provided 105 with a slot 22 extending within the same, the height of which is such as to permit the head 9 to rest at its upper extreme, while the part 11 of said rocking arm is of such size to fit snugly within the slot, while the lower edge 110 of the flange 21 rests upon the flat part 12 of the rocking arm and affords a substantial

110

bearing to support said grate bar. It will now be seen how readily any particular grate bar may be removed without disturbing in any manner any other grate section, 5 or any part or parts that may be connected to the rocking arm, for the manipulation of said grate. The angle of the underlapping lip 19 at the front, the same angle being provided for the slot 22, and the overlapping 10 lip 20 of the rear of the grate bar permits of said grate bar being removed without any trouble.

Each of the several sections of grate bars are made in like manner, and as has been 15 noted all are interchangeable at will, any number of sections of grate bars may be employed, and each of the several sections so connected with well known means that they may be suitably operated. The new and 20 very important feature herein, is that each section is provided with said underlapping and overlapping edges and being mounted on the rocking arm 8 so that the section may be removed. 25 As shown in Fig. 4, the grate bar is shown with the slot 22 so modified as to have one vertical face as shown at 23, in which case it also permits of the individual grate bar being lifted off the rocking arm 8 for any purpose whatsoever, such for instance as changing it from one place to another if thought necessary, or for replacing it, should it be broken or warped out of condition. Of course, it will be understood that any one 30 skilled in the art may vary the angles of such inclines at the ends of the grate bar, also the slots which fit over the rocking arm, as it is apparent that the invention is susceptible of various modifications in its design. 35 tails, such as that suggested, and hence is not restricted to the exact construction here shown.

Again as shown in said Fig. 4, the rocking arm may be so arranged, that its respective 45 contact faces 9, 11 and 12 will contact with the respective faces of the flange or flanges 21 of the grate bar. It is very important that it be understood that the present invention contemplates the head 9, of the rocking arm 8, fitting the top of the slot 22 closely. The sides of the slots 22 are also formed so as to closely embrace the member 11 and aline with the sides of said member, so as to hold the grate bar steady on the 50 arm 8. The bottom 24 of the flange 21 should also rest evenly upon the upper surface of the flange 12. By this means of support, greater strength and longer life are secured for the grate bars, as they will not 55 warp as readily as when supported in bearings at the front and back.

Again it will be further understood that while the preferred form is shown, yet it will be readily understood that in lieu of a 60 single flange, or of side flanges as at present

preferred, provided with suitable openings which are adapted to fit over and rest upon the rocking part, that a single web or a plurality of webs could be provided from each of which could extend an arm, the angle of which would conform to the same angle as the over and under lapping ends, and suitable pockets or other means provided in the rocking part to securely hold the same therein. Such an adaptation of the invention, is another change that may be made as has been noted, and any other like modification would come within the purview of the invention.

Grate bars have been made to rock by various devices, such as having a pivoted joint at one end, and having means at its other for rocking the same. Again they have been so designed so as to rest on a rocking arm, the slot being for the purpose of straddling the rocking means, but this is objectionable as they warp, and by reason of having only one bearing point, such sections must necessarily be replaced often. So also have grate bars been provided with over and underlapping lips, but in no case have such grate bars been provided with such over and under lap- 85 pings ends at the front and rear, and also with a slot so arranged in its flange, flanges, or sides, whereby the intermediate grate bars 90 may be removed from the rocking arm without disturbing any connecting part or adjacent grate or grates on the same or other rocking arm.

Having now described my invention, what 100 I claim and desire to secure by Letters Patent of the United States is:

1. A grate bar, downwardly extending side flanges on said bar, said flanges being provided with angularly disposed open slots, 105 a rocker arm comprising an angularly disposed portion adapted to enter and conform to the shape of said slots, a laterally disposed flange portion which forms a seat for the flanges of the grate bar, and a downwardly extending finger, and a lever engaging said finger to rock said grate bar.

2. A grate bar, downwardly extending side flanges on said bar, said flanges being provided with slots, a rocker-arm adapted 115 to enter said slots comprising a flanged portion, a cylindrical portion, an angularly disposed neck connecting said portions, and a downwardly extending finger connected to the flanged portion for operatively connecting the bar to the grate rocking means.

3. A grate bar, side flanges on said bar provided with downwardly and forwardly inclined slots positioned to one side of the longitudinal axis of said bar, a rocker bar 125 adapted to enter said slots and providing a seat for the side flanges of the grate bar, and means for oscillating said rocker bar.

4. A grate bar, side flanges on said bar, said side flanges being provided with open 130

slots, a rocker bar adapted to enter said slots, laterally extending flanges on said rocker bar which form a seat for the flanges of the grate bar, the slots in the flanges and the rocker bar being so disposed as to permit each grate bar to be removed without disturbing any other section by elevating the same rearwardly in the direction of the slots, and means for oscillating the rocker bar.

5. A grate bar, downwardly extending side flanges on said bar, a rocker bar having

laterally extending flanges which form a seat for the flanges of the grate bar, means at an angle to the plane of the bar for holding it 15 securely to the rocker bar, and means for oscillating the rocker bar.

In testimony whereof, I have signed my name in the presence of two subscribing witnesses.

JOHN J. SHEVLIN.
